IMPROVEMENT IN BRAN DUSTERS.

GEO. H. REYNOLDS, OF PEORIA, ILLINOIS.

Letters Patent No. 59,862, dated November 20, 1866.

SPECIFICATION.

TO ALL WHOM IT MAY CONCERN:

Be it known that I, GEORGE H. REYNOLDS, of Peoria, in the county of Peoria, and State of Illinois, have invented a new and useful improvement in Bran Duster; and I do hereby declare that the following is a full, clear, and exact description thereof, which will enable others skilled in the art to make and use the same, reference being had to the accompanying drawings, forming part of this specification, in which—

Figure 1 is a top view of my improved bran duster, partly in section through the line zz , figure 2.

Figure 2 is a vertical longitudinal section of the same taken through the line xx , figure 1.

Figure 3 is a detail side view of the upper part of the apparatus.

Figure 4 is a horizontal cross section of the same taken through the line yy , figure 2.

Similar letters of reference indicate like parts.

My invention has for its object to furnish an improved apparatus by means of which the flour adhering to the bran may be readily and thoroughly separated therefrom, and it consists, first, in the combination of the convex and concave cones, constructed as hereinafter described, with each other, with the driving shaft, and with the frame of the apparatus; second, in the combination of the stationary and movable spiked heads with each other, with the driving shaft, and with the frame of the apparatus; third, in the combination and arrangement of weights, levers, uprights, and cams, and gear wheels, with each other, with the driving shaft, with the frame of the machine, and with the frames to which the wire bolt cloth is attached.

A is the frame of the machine, B is the central or driving shaft; this shaft is vertical and it is supported, and its lower end revolves in a step, C, as shown in figure 2. This step is cup-shaped to contain the lubricating oil, and it is covered with a cup, c' , to keep out the dust and dirt. The upper end of the shaft, B, revolves in bearings D, attached to the frame, A, of the machine; E is a convex cone attached to the upper part of the shaft B. This cone may be made double, as shown in the drawings, or it may be made single, as may be desired. Upon the convex surface of the cone E, are formed ribs, e' , which are notched or toothed as shown in figures 1 and 2. F is a concave cone surrounding the cone E, as shown in the drawings. The inner or concave surface of this cone is ribbed to correspond with the ribs formed upon the convex surface of the cone E. These ribs, f' , are also toothed or notched in such a way that the projections of the ribs f' may enter and work in the notches in the ribs, e' , as shown in figure 2, when the shaft B and cone E are revolved. To the lower side of the platform G, that supports the cone F, is attached an immovable head, H, the lower surface of which is filled with downwardly projecting spikes, as shown in figure 2. The middle part of the head H, is cut away as shown, so that the bran may pass freely from the space between the convex and concave cones to the space between the immovable head H and the movable head I. The movable head I is attached to the shaft B, and has its upper surface filled with spikes so arranged as to pass between the spikes of the head H, as shown in figure 2. The head I is of such a size as to leave a space all around its edge, through which the bran may pass into the bolt beneath. To the lower surface of the movable head I is attached the upper ends of the wings J, the lower parts of which are attached to arms, K, extending out from the shaft B, as shown in figures 2 and 4. The forward or outer edges of the wings, J, are notched as shown and they are set inclined; the lower end of each wing being in advance of the upper end, so that the tendency of the wings may be constantly to uplift the bran. L is a spout through which the bran finally escapes from the duster. M is the wire bolt cloth which is attached to a framework, consisting of vertical ribs, N, and circular end pieces, O. The spaces between the vertical ribs lead through holes in the bottom, P, of the bolt, into the chamber R, formed between the bottom, P, of the bolt and the bottom, S, of the duster. T is the outer casing that encloses the bolt. U are arms attached to the shaft, and which, as the shaft revolves, sweep around the chamber, R, moving the flour into such a position that it can escape through the spout V. To the upper end of the shaft B is attached a pinion wheel, W, the pinions of which mesh into the teeth of the wheel X, which revolves upon a spindle, A', attached to the frame, A, of the duster. Upon the lower side of the wheel X are formed two or more cams, B', as shown in figure 2, which as the said wheel revolves come in contact with the upper ends of the uprights C', and depress them. The lower ends of the uprights C' rest upon and are pivoted to the ends of the levers D', as shown in figure 3. To the other ends of the levers D' are pivoted the ends of the levers E', the other ends of which are pivoted to the frame, A, of the duster, as shown in figure 1. F' are weights attached to the levers D' and E', which rest upon the heads of the pins G'. These pins pass through the platform G, and their lower ends rest upon the upper end pieces, O, of the frame to which the bolt cloth M is attached, as shown in figure 2. As the upright C' are depressed by the

cams B', they operate the levers D' and E', and raise the weights F', which, when the uprights are freed from the cams, fall upon the pins G' and jar the bolt cloth so as to keep the meshes open for the passage of the flour. The bran may be introduced into the hopper, H', from a shaker by means of which cobs, nails, dough-balls, &c., which may be in the bran, are separated from it before it enters the duster. The bran upon entering the duster passes down between the convex and concave cones, into the space between the immovable and movable heads H and I, thence it passes down around the edge of the movable head I into the bolt, and then out through the spout L. The flour disengaged from the bran during its passage through the duster, passes through the bolt cloth M, and thence down into the chamber R, from which it passes out through the spout V.

What I claim as new, and desire to secure by Letters Patent, is—

The bran duster consisting of the ribbed cone E, ribbed encasing cone F, spiked stationary head H, spiked movable head I, winged arms K, bolt-frame M, chamber R, arms U, enclosing case T, uprights C', weighted levers D', and levers E', arranged and operating substantially as described for the purpose specified.

GEO. H. REYNOLDS.
